UNITED STATES PATENT OFFICE.

HARRY PFANNENSTIEHL, OF MAPLEWOOD, NEW JERSEY, ASSIGNOR TO WESTERN ELECTRIC COMPANY, INCORPORATED, OF NEW YORK, N. Y., A CORPORATION OF NEW YORK.

DISTRIBUTING APPARATUS.

Application filed November 1, 1920. Serial No. 420,902.

To all whom it may concern:

Be it known that I, HARRY PFANNENSTIEHL, a citizen of the United States, residing at Maplewood, in the county of Essex, State of New Jersey, have invented certain new and useful Improvements in Distributing Apparatus, of which the following is a full, clear, concise, and exact description.

This invention relates to distributing apparatus, and particularly to an improved type of apparatus for distributing current impulses of desired length in proper sequential order. The invention is particularly applicable for use in printing telegraph systems of the multiplex synchronous type, although obviously not limited to such use.

An object of this invention is the provision of means whereby the distributing apparatus at one station may be brought into the desired phase relation or into synchronism with a similar distributing apparatus at a remote or distant station, in a reliable and efficacious manner.

For the accomplishment of the above object, the invention contemplates the provision of a distributor face provided with a plurality of rings, some of which are segmented and others continuous, and adapted to be interconnected by conducting brushes carried by rotatable distributor arms. The distributor arms are motor driven and are adapted to be rotated normally at a uniform, predetermined speed, with means provided whereby the speed of the distributor brushes may be altered momentarily or the phase relation of a plurality of distributor arms changed while they are rotating. The preferred embodiment illustrated in the accompanying drawing comprises a plurality of distributor faces, preferably arranged in separate parallel planes, each distributor face provided with separate and independent brushes. The distributor brush arms may be orientated while they are rotating and independently of one another.

The invention is herein illustrated as applied to a multiplex telegraph system, but it is to be understood that it is equally suitable for other signaling systems wherein it is desired to distribute current impulses of definite length in a predetermined or sequential order.

The above and other features of this invention will be fully set forth in the following description and claims and will be more

readily understood by reference to the accompanying drawings, wherein Fig. 1 is a side elevation of a current impulse distributing apparatus with a part thereof shown in cross section; Fig. 2 is a view on line 2, 2 of Fig. 1, looking to the left; and Fig. 3 is a view on line 3, 3 of Fig. 1, looking to the right.

Referring to Fig. 1, the power shaft 10 is driven by a motor 11 of any well-known construction. Concentric with the power shaft 10 is a plurality of current impulse-distributing faces which, in a multiplex telegraph system, may be considered correcting, receiving and sending faces, marked C, R and S, respectively. Each face is provided with one or more pairs of rings, as illustrated in Fig. 2, one ring of each pair being continuous and the other segmented. Each pair of rings is provided with a set of distributor brushes for the purpose of connecting the segments of the segmented ring with the continuous ring. The brushes are carried by brush arms 12, secured to a sleeve or collar 13, one end of which is formed into a bevel gear 14. The bevel gear 14 and collar 13 are loosely mounted on the shaft 10 by means of bearings, as indicated at 15. Associated with each gear 14 is a second bevel gear 16, which is keyed or rigidly secured to the driving shaft 10. Intermediate the pair of gears 14 and 16 is a third gear or idler 17, carried by a shaft 18 and mounted in ball-bearings 19 carried by a support 20. The support 20 is rigidly secured to a normally fixed disc 21 mounted concentric with the shaft 10 and adapted to be turned or orientated by hand. The disc 21 at its periphery is turned over at a right angle, partially enclosing the frame or supporting portion 22 of the distributor head. The center portion of the disc 21 is cut away and is held in frictional engagement with the distributor head frame 22 by means of a circular plate 23. The frictional engagement between the frame 22, circular plate 23 and disc 21 may be varied or adjusted by means of the screws 24 and springs 25 carried thereby.

It will be seen that when the driving shaft 10 is rotating, the distributor brush arms 12 will revolve at the same R. P. M. as that of the driving shaft; but if, for any reason, synchronism is lost between a distributor at one station and a correspond-

- ing distributor at a remote station, the speed of the distributor arm at either station may readily be changed, or the desired phase angle between the distributor brush arms 5 may be secured easily and quickly by rotating the disc 21 to which the gear 17 is secured. The disc 21 may be rotated by hand either clockwise or counter-clockwise, depending upon whether the distributor arm 10 at that particular station is ahead or behind the corresponding distributor arm at the remote station. In other words, the disc 21 may be turned in whichever direction necessary in order to restore synchronism, the 15 most expeditiously. It will be noted that the disc 21, and likewise its corresponding distributor brush arm, may be rotated through any number of degrees required.

At the top of each distributor head and 20 adjacent the overturned portion of the corresponding disc 21, is a graduated scale 26 to indicate the number of degrees or extent of orientation of the corresponding disc.

- 25 On the driving shaft 10 and adjacent the motor 11, is mounted a fly-wheel 30, which may be of any desired construction, for example, such as disclosed in Patent 1,271,362 issued to P. M. Rainey on July 2, 1918, 30 for damping out speed fluctuations.

This type of distributing apparatus is well suited for various kinds of service where it is necessary that the receiving and sending distributors be kept in synchronism, 35 and is particularly well suited for service on lines where there are a number of receiving stations, receiving from a lesser number of sending stations. If, for some reason, any one of the receiving stations 40 should get out of synchronism with the sending station, the receiving operator at that station may regain synchronism quickly and efficiently by simply rotating or orientating the disc 21 of the receiving distributor until the signals are received in their 45 proper place. This condition may be indicated by a recording instrument, such as a printer or an indicating means, such as disclosed in Patent No. 1,388,507, issued August 23, 1921, may be used.

50 What is claimed is:

1. A distributing apparatus comprising a distributor face, conducting rings and segments carried by said face, a rotatable brush arm, brushes supported by said arm and adapted to sweep over said conducting rings and segments, means for rotating said brush arm at a definite predetermined speed, and manual means for orientating the brush arm 55 in either direction while rotating.
2. A distributing apparatus comprising a distributor face, conducting rings and segments carried by said face, a rotatable brush arm, brushes supported by said arm and 60 adapted to sweep over said conducting rings

and segments, means for rotating said brush arm at a definite predetermined speed, and manual means for orientating at will the brush arm through variable distances.

3. A distributing apparatus comprising a 70 distributor face, conducting rings and segments carried by said face, a rotatable brush arm, brushes supported by said arm and adapted to sweep over said conducting rings and segments, means for rotating said brush arm at a definite predetermined speed, and means for advancing or retarding the distributor arm variable amounts while said arm is rotating.

4. A distributing apparatus comprising a 80 distributor face, conducting rings and segments carried by said face, a rotatable brush arm, brushes supported by said arm and adapted to sweep over said conducting rings and segments, means for rotating said brush arm at a definite predetermined speed, and manual means comprising a disc and differential gear for altering the speed of the distributor brush arm.

5. A distributing apparatus comprising a 90 distributor face, conducting rings and segments carried by said face, a rotatable brush arm, brushes supported by said arm and adapted to sweep over said conducting rings and segments, means for rotating said brush arm at a definite predetermined speed, and manual means comprising a disc and differential gear for orientating the brush arm.

6. A distributing apparatus comprising a distributor face, conducting segments carried by said face, a rotatable brush arm carrying brushes cooperating with said segments, means for rotating said brush arm including a differential gear, and means for altering the speed of said brush arm 105 through the instrumentality of said gear.

7. A distributing apparatus comprising a plurality of distributor faces, conducting segments carried by each of said faces, a rotatable brush arm individual to each face, brushes supported by each arm and adapted to sweep over said conducting rings and segments at a definite speed, and means for orienting each brush arm independently of the other.

8. A distributing apparatus comprising a plurality of distributor faces, conducting segments carried by each of said faces, a rotatable brush arm individual to each face, brushes supported by each arm and adapted to sweep over said conducting rings and segments at a definite speed, and manual means for orienting each brush arm while rotating independently of the other.

9. A distributing apparatus for printing telegraphs comprising a distributor face, conducting rings and segments carried by said face, a rotatable brush arm, brushes supported by said arm and adapted to sweep over said conducting rings and segments,

means for rotating said brush arm at a definite predetermined speed, and manual means for shifting the position of the brush arm to any position in one continuous movement.

10. A distributing apparatus for printing telegraphs comprising a distributor face, conducting rings and segments carried by said face, a rotatable brush arm, 10 brushes supported by said arm and adapted to sweep over said conducting rings and seg-

ments, means for rotating said brush arm at a definite predetermined speed, and manual means for effecting an angular displacement of said brush arm in either direction to any desired position in one continuous movement.

In witness whereof, I hereunto subscribe my name this 23rd day of October A. D., 1920.

HARRY PFANNENSTIEHL.
